(57) **CLAIM**

The ornamental design for a bicycle fork, as shown and described.

DESCRIPTION

FIG. 1 is a perspective view of a bicycle frame including the claimed bicycle fork;

FIG. 2 is a top plan view of the bicycle fork;

FIG. 3 is a side view of the bicycle fork;

FIG. 4 is a front view of the bicycle fork;

FIG. 5 is a rear view of the bicycle fork;

FIG. 6 is a bottom view of the bicycle fork; and,

FIG. 7 is an enlargement view of a front end portion of the bicycle fork.

The portions of the bicycle fork shown in broken lines form no part of the claimed design. The dash-dot lines are provided to define the bounds of the claim but do not form part of the claimed design.
